UNITED STATES PATENT OFFICE.

MILLARD F. COX, OF LOUISVILLE, KENTUCKY.

PACKING-RING EXPANDER.

1,316,534.

Specification of Letters Patent. Patented Sept. 16, 1919.

Application filed June 18, 1917. Serial No. 175,485.

To all whom it may concern:

Be it known that I, MILLARD F. Cox, a citizen of the United States of America, residing at Louisville, in the county of Jefferson and State of Kentucky, have invented certain new and useful Improvements in Packing-Ring Expanders, of which the following is a specification.

This invention relates to packing rings, or 10 packing expanders, and one of the objects thereof is to provide durable and efficient means for maintaining a close contact between a stationary part and a movable part, as for example, between a piston and its cylinder.

Other objects and advantages of this invention will become apparent hereinafter, it being understood that changes in form, proportion and minor details of construction 20 may be resorted to without departing from the spirit of the invention or sacrificing any of the advantages thereof.

In the drawing:

Figure 1 is a plan view of a packing ring 25 constructed in accordance with my invention.

Fig. 2 is a sectional view on the line 2—2 of Fig. 1.

Fig. 3 is a sectional view on the line 3—3 30 of Fig. 1.

Fig. 4 is a fragmentary view of one of the ends of the ring.

Fig. 5 is a fragmentary sectional view 35 through a portion of a cylinder, piston and packing, and

Figs. 6 to 18, both inclusive, are detail sectional views through different forms of the ring.

I have selected the form of ring shown in 40 Figs. 1 to 6, as the preferred form, and this consists of a ring 1, folded and pressed from a single piece of sheet metal, as for example steel, into concavo-convex cross sectional form, the metal being doubled back upon 45 itself to form a double wall, although it is not necessary to follow this procedure in all the forms. The ring is so constructed that at least one of the walls thereof is under tension when applied to the packing, as for

50 example between the piston 2 and the packing 3 to insure a close contact between the packing and the cylinder 4. Of course, both walls of the ring may be under tension, but this is not necessary under all conditions.

55 Inasmuch as the rings are adapted to be

sold separate from the engine, compressor or other device with which they may be used, it is desirable that the ends 5 and 6 do not spring apart, as they make a better appearance if they retain their circular 60 shape. To this end, the inner walls of the spaced ends 5 and 6 are folded inwardly toward the outer walls as at 7 and 8 so as to form guides for the dowel or pin 9 preferably fastened at one end to one of the bent-over walls and slideable in the guide formed by the other, whereby a slip joint is provided. This also assists in placing the rings in position, as the ends 5 and 6 cannot spring apart a sufficient distance to destroy the circular formation of the ring. Holes or openings 10 may be provided for the purpose of lubrication. I have shown the inner wall of the ring in Figs. 1 to 5 as of slightly less height than the outer wall. The purpose of 75 this will be apparent by reference to Fig. 5, from which it will be seen that the inner wall fits under the top of the piston head, while the outer or higher wall is free to bear against the packing 3 and thereby cause it 80 to bear snugly against the cylinder 4. In the particular instance just described, the higher or outer wall will have sufficient compression against the packing to accomplish 85 the end desired.

In Fig. 7, the metal is doubled upon itself for the entire distance instead of partially, as shown in Figs. 1 to 6, so that the walls 11 and 12 are of the same thickness.

In Fig. 8, the higher wall 13 is formed 90 with a lateral projection or bracing flange 14 at its upper edge to provide rigidity and strength to said wall.

Fig. 9 illustrates a spring wall 15 as circular, and in this case, both the wall 15 and 95 the one designated 16 are of single thickness.

Fig. 10 discloses a vertical wall 17 of single thickness and a laterally curved wall 18 of double thickness, the end of the wall 18 being spaced from the wall 17.

Fig. 11 shows a construction similar to that shown in Fig. 10, but in this case, the end of the curved wall 19 is close to the vertical wall 20.

In Fig. 12 the vertical wall 21 is provided 105 with an outwardly turned flange 22 of single thickness, while the curved wall 23 is double.

Fig. 13 shows a vertical wall 24 of single thickness and a circular wall 25 of double thickness.

In Fig. 14, I have shown a construction similar to that shown in Fig. 6 with an in-bent lateral bracing flange 26.

Fig. 15 is similar to Fig. 6, but provided at the free ends of the walls 27 and 28 with lateral bracing flanges 29 and 30.

In Fig. 16, the ring consists of a vertical wall 31 and a circular wall 32, both of single thickness, but in this form, the circular wall is not partially coiled as in Fig. 9.

Fig. 17 shows a ring with a vertical wall 33 and a lateral flange 34 at its lower edge, both walls being of a single thickness, while in Fig. 18, the vertical wall 35 in addition to the lower flange 36 is provided with an oppositely disposed lateral flange 37 at its upper edge.

In those forms of ring susceptible to em-

ploying the slip joint, I prefer to bend over the walls adjacent to the ends thereof, although the slip joint is not essential in all cases.

I claim:

1. A packing expander comprising a concave and convex ring of channel form constructed with folded walls presenting a double thickness and a lateral flange projecting from one of the walls of said ring.

2. A packing expander comprising a folded sheet constructed of metal rolled to channel form and having lateral flanges on the longitudinal edges of the sheet.

In testimony whereof the foregoing specification is signed at Louisville, Kentucky, this 6th day of Oct., 1916.

MILLARD F. COX.
